UNITED STATES PATENT OFFICE.

EMANUEL RICHTER, OF CHICAGO, ILLINOIS, ASSIGNOR TO THE ELLIOTT-FISHER COMPANY, OF NEW YORK, N. Y., A CORPORATION OF DELAWARE.

CALCULATING MACHINE.

Application filed March 24, 1906. Serial No. 307,942.

To all whom it may concern:

Be it known that I, EMANUEL RICHTER, a citizen of the United States of America, residing at Chicago, in the county of Cook and 5 State of Illinois, have invented certain new and useful Improvements in Calculating Machines, of which the following is a description.

My invention belongs to that class of devices particularly designed to mechanically calculate the sum or difference between the sums of a plurality of columns of numbers and has for its object the production of a more simple, accurate, and durable device 15 for the purpose set forth.

To this end my invention consists of the novel construction, arrangement and combination of parts herein shown and described and more particularly pointed out in the 20 claims.

In the drawings, wherein like reference characters indicate like or corresponding parts,

Figure 1, is a top plan of my improved 25 device,

Figure 2, is a similar view with the top plates removed to more clearly show the working parts,

Figure 3, is a continuation of view shown 30 in Figure 2, the sheet containing the same being intended to be placed at the bottom of the sheet containing Figure 2, to complete the top plan of the structure,

Figure 4, is a vertical section in line 4—4 35 of Figure 2, viewed in the direction indicated by the arrow,

Figure 5, is a section taken in line 5—5 of Figure 4, viewed in the direction indicated by the arrow,

Figure 6, is an end elevation with the casting broken away to show the construction,

Figure 7, is a side elevation with the casting removed, showing the construction as viewed from the left in Figure 5,

Figure 8, is a detail perspective view of the carriage and its connections, together with parts of the reversing mechanism, said view being taken from the direction of the upper left hand corner of Figure 2,

Figure 9 is a detail perspective view of the indicating wheels, showing the locking and carrying mechanism for the same.

Figures 10 and 11, are detail views of a portion of the transmitting mechanism, 55 showing the parts in different positions,

Figure 12, is an end view of one of the numeral or indicating wheels,

Figure 13, is a diametrical section of the same showing the construction of the operating clutch therefor,

Figures 14, 15 and 16, are detail views of the escapement mechanism, controlling the lateral movement of the carriage,

Figure 17, is a partial section in line 17—17 of Figure 16,

Figure 18, is a partial detail plan with parts broken away, showing a modification of my improvement,

Figure 19, is a detail view of a part of the reversing mechanism, and

Figure 20, is a detail view.

As shown in the drawings, 1 is a suitable casing or frame provided with a plurality of vertically movable keys 2 each provided with an inclined section 3 or equivalent means for a purpose hereafter stated. Figure 4). 4, is a longitudinally movable bar provided with an anti-friction roller 5 arranged in the path of and adapted to contact with the inclined face 3 of the keys 2. 80 (Figures 4, 10 and 11). The number of bars 4 preferably corresponds with the number of keys 2. A plurality of longitudinally movable stop bars 11, are each provided with a shoulder or stop 13, or an equivalent part arranged in the line of travel of the bars 4. A transverse shaft 9, has loosely mounted thereon a plurality of arms or levers 10, each of which levers is connected to a bar 11, in any preferred manner. As 90 shown this is accomplished by the connecting link 12, pivotally connected to the end of a stop bar 11, and to an arm 10. As any one of the bars 11, is reciprocated, therefore, the lever 10, will be loosely oscillated on the 95 shaft 9. As previously stated the several shoulders 13 are constructed in line with the longitudinal travel of the bars 4, so as to contact therewith and be operated thereby.

The several shoulders 13, however, are arranged at different points on the several bars 11, so as to extend in a diagonal direction across the several bars as shown in Figures 2, and 3. As a key 2, is depressed its movement causes the longitudinal movement of its bar 4, which contacting with the shoulder 13, on a bar 11, longitudinally moves the same and oscillates the arm 10. Inasmuch as the travel of the bar 4 is always the same no matter which of the keys may 110

be depressed; the several shoulders are positioned diagonally as described, so that with the same longitudinal movement of the bar 4, the several bars 11 will have a different or varying limit of travel or movement as hereafter stated. This varying movement of the travel of the several bars 11, also varies the oscillation of the arms 10, upon the shaft 9, on which shaft the arms are loosely mounted. Means are provided to return the bar 4, to its normal position as shown in Figure 4. This may be accomplished in any preferred manner. As shown a spring 15, connected to said bar at one end and at the other end to a fixed part or portion of the frame accomplishes this purpose. Similarly springs 21, or equivalent means return the several bars 11, to their normal position. (See Figures 4, 5, 10 and 11.)

20 A ratchet wheel 16, or an equivalent part is fixed to the shaft 9, near each arm or lever 10, and a pawl 17, carried by the said lever engages the teeth of the ratchet wheel and rotates the same and the shaft 9, as 25 the lever is oscillated. (See Figures 4, 10 and 11, also Figure 7.) The shaft 9, carries a cog-wheel 18, secured thereto, (Figures 2, 5 and 7,) which meshes with a pinion or cog-wheel 19, secured to a shaft 20, 30 extending parallel to the shaft 9. The varying partial rotation of the shaft 9, caused by the depression of any of the keys 2, is therefore, transmitted to the shaft 20. Upon the shaft 20, are loosely mounted a 35 plurality of indicators, numeral wheels or denominational members 22, maintained in relative position upon the shaft in any preferred manner. As shown in Figure 13, a circumferential groove 23, is formed in the shaft, in which a pin or projection 24, 40 on the wheel is loosely seated. In the preferred construction two or more series of such numeral wheels are employed as clearly shown in Figure 2. Each series of number 45 wheels constitutes a totalizer, receiving mechanism, register or computing device, as it is variously termed in the art. Each wheel 22, is formed with a part of its periphery 25, cogged and extending partly across its face, for a purpose hereafter 50 described. One member 26 of a clutching device is also secured to and carried by the wheel. (Figure 9, and 13). The other member 27, of the clutch device is loosely 55 splined, keyed or otherwise so secured to the shaft 20, as to rotate therewith and at the same time be permitted a longitudinal movement thereon. A parallel shaft 28, is 60 arranged near the shaft 20, and has loosely mounted thereon a plurality of carrying and locking wheels 29. These wheels are longitudinally movable on the shaft 28, and are normally held in proper relative position by springs 30 or equivalent means arranged for that purpose (Figure 2). The

carrying and locking wheels 29, are each provided with a part 31, cogged to mesh with the part 25, of its companion wheels 22, with which it is constantly in mesh the two being formed to permit the movement 70 of the wheel 29, longitudinally the shaft 28, without disengaging them. The wheel 29 is also provided with a cogged part 32, preferably provided with alternate short cogs 33, and long cogs 34, while between the 75 two parts 31 and 32, provision is made for engaging shifting mechanism. As shown the pivoted lever 35, has it extending arms 36, 36, (Figure 8) adapted to engage with a central peripheral groove 38, in the wheels 80 29, (Figure 9). The numeral wheels 22, are each provided with a single peripheral groove 39, formed to engage the larger cogs 34, of the wheel 29, as the numeral wheel is rotated and thus advance the wheel 29, 85 a sufficient distance to carry the numeral wheel engaging the cogs 31, one interval. This constitutes my carrying means. In the preferred form an extension 40, is formed on the side of the numeral wheels 90 which as the latter are rotated, first contacts with one of the shorter cogs 33, partially rotating the wheel 29 and positively engaging the longer cog 34, with the groove 39. The distance between two of the larger 95 cogs 34, is so proportioned that they will be positioned at all times, except when advancing, to ride upon the periphery of the adjacent numeral wheel when engaging with the same, as shown in Figure 9, while 100 the cogged part is at all time in mesh with companion numeral wheel. The numeral wheel at the left in Figure 9, is therefore, effectively locked against accidental displacement or rotation. This, the normal 105 position is maintained until the wheel 29, by the operation of the device is moved to the left, (Figure 9) a sufficient distance for the same to clear the numeral wheel to the right as will be hereafter explained. 110

The levers 35, are each pivotally connected to a fixed part 41, and each engages a clutch member 27, as well as a wheel 29, with the exception of those on the extreme right of the series of numeral wheels (Figure 2). A movable slide 42, or equivalent part is arranged to contact with each lever 35, and by its movement oscillate the lever on its fulcrum 41. When released the spring 30, on the shaft 28, or other suitable means return the parts to their normal positions. 115

A transversely movable carriage 43, (Figures 1, 2, 8, 5, and 18,) is arranged in suitable guides or ways, and an extension 44, preferably provided with an anti-friction roller 45, extended in line with the several arms 42, so that in passing it will contact with the inclined faces 46, of the several slides 42, and longitudinally 120 125 130

move said slides and operate the levers 35, and the parts dependent thereon. The extension 44, is pivotally supported at 47, a spring 48, holding it normally in position. 5 Thus while substantially fixed and rigid when moving in one direction as toward the right and thus operating the several slides 42, on reversing the movement and moving the carriage in the opposite direction to return it to its proper operating position, the contact will depress the spring 48, and not operate said arms. In the preferred form a spring pulley 49, driven by a spring 50, (Figures 2, and 5,) together 10 with a strap or band 51, (Figure 4) secured at one end to the periphery of the pulley and at the other end to the carriage, tends to draw the carriage in that, its operative, direction, as in well known forms 15 of typewriters.

Referring now particularly to Figures 4, and 6, a transverse shaft 52, is arranged near the keys 2, and provided with a plurality of extending arms 53, corresponding in number 20 with the keys and each adapted to contact with the face of a rib 53.1/2, formed on the keys, or an equivalent part, when the latter are depressed. The several arms 53, are keyed or otherwise secured to the shaft 25 and as a result depression of any one of the several keys will rock or partially rotate the shaft 52. A depression X, is formed on the face of the ribs 53.1/2, at a proper point within which the head Y, of the arms 53, 30 may be seated when the parts are in their normal position (see Figure 4). Until the key reaches its normal position, therefore, the arm 53 cause the shaft 52, to retain a partially rotated position, as will more fully be 35 explained hereafter. One of the arms 53, contacts or engages with a longitudinally movable bar 55, provided with escapement trip arms 56—56 (Figures 4, 14, 16, and 17). A spring 57, tends to return the bar to its 40 normal position. A shaft 58 is provided with an escapement wheel 59, loosely mounted thereon and provided with projecting teeth 60, co-acting with the trip arms 56, to limit the rotation of the wheel and its shaft, 45 in a manner employed in typewriters and similar devices. Any preferred means may be employed to retain the escapement wheel in proper relative position on the shaft. As shown in Figure 16, a circumferential groove 55 61 is formed on the shaft and a pin 62, extending through a sleeve on the wheel into the groove keeps the parts in position. An internal ratchet wheel 63, is secured to the shaft 58, by a key 64, or equivalent means, 60 and a pawl 65, carried by the escapement wheel 59, co-acting therewith permits the shaft 58 to be rotated in a reverse direction without disturbing the escapement wheel 59. The shaft 58, has also fixed thereto a cog- 65 wheel 66, meshing with a cog-rack 67, se-

cured to the carriage 43, (Figures 4, 5, 8, and 14).

It will thus be seen that the tendency of the connection of the spring pulley 49, is to draw the carriage toward it and the engagement of the cog-rack 67 with the cog-wheel 66, together with the escapement and its connections causes the depression of any key to permit the forward movement of the carriage one interval as in typewriters and similar devices. In the machine shown in the drawings the movement of the carriage is toward the right when in operation.

The operation as thus far described is as follows, referring particularly to Figure 3, 80 and to the lower half of Figure 2, where two series of numeral or indicator wheels are shown to enable two columns of numbers to be separately totaled, as well as to Figures 4, 5, 6, 7, and 8, and the detail drawings 85 referred to. The operator having before him two columns of numbers, which may represent the debit and credit side of an account as shown on a ledger, he begins by indicating the numeral of the highest 90 order. Thus if the first number in the column be 1234.62, he will place the carriage so that the extension 44, is to the left of the movable arm 42, operating the numeral wheel indicating thousands which as shown 95 in the drawings, will be the arm 42, to the extreme left. By pressing the key 1, the movement of the key operates the escapement permitting the carriage to move to the right a part of one interval. The extension 100 44, will contact with the inclined face 46, of the arm 42, and longitudinally move said arm, operating the lever 35, and the clutches 26 27, and releasing the first numeral wheel 105 from the interlocking connection with the second numeral wheel by the movement of the wheel 29, longitudinally the shaft 28, as described. The extension 44, rests against the end of the slide 42, holding the parts in the position described until the key is released. While this operation is taking place 110 the arm 4, (Figure 4) is longitudinally moved contacting with the shoulder 13, and longitudinally moving the proper bar 11, the predetermined distance. the arm 10 115 is oscillated, the ratchet wheel 16, shaft 9, cog-wheels 18, and 19, and shaft 20, are all rotated the proper distance to rotate the first numeral wheel to indicate the proper numeral, all the parts being timed to 120 promptly and accurately perform this operation. As the key is released the several springs and the construction described return the parts to their normal positions. The first numeral wheel being retained and 125 locked by the wheel 29, as described, in the position assumed. In like manner the remaining numerals going to make up the number are indicated the operator successively operating the 2, 3, 4, 6, and 2, keys. 130

In like manner the next number is indicated. If, for example the next number be 963.43 the addition will necessitate the carrying from one order to another at two points, the fifth and the second. Moving the carriage to the left so that the extension 44, is just to the left of the second slide 42, from the left indicating the order of hundreds the spring 48, permitting the extension 44, to pass by the several bars 42, and pressing the key 9, the operation will be as before described with the exception that as the second indicator wheel 22, already has 2, indicated the addition of 9, will more than complete its rotation or cycle, and as it completes its cycle the extension 40, on the wheel 22, contacts with the short cog 33, on the wheel 29, partially rotating said wheel to positively engage the cog 34, with the groove 39, and rotating the first numeral or indicator wheel to the left, one interval, carrying one to that order and thus indicating 2, where before it indicated 1. The balance of the number is indicated in the same manner one being also carried to the third order. When the debit has been fully added as set forth, the indicators will show the total footing.

For adding the credit column the carriage is moved to the right to operate the second series of indicator wheels and the operation is the same. When the operation is completed the total footings of both the debit and credit columns will be indicated side by side in proper relative positions, greatly facilitating the labor and avoiding errors, the accuracy in computing being assured.

In the drawings I have shown the numeral or indicator wheels in series of six. Thus arranging to indicate up to the sixth order, or in the case of dollars and cents to indicate cents and the value of dollars up to the thousands place. It is obvious however that these may be increased or decreased as desired, to adapt the device to any particular use or business. Consequently I do not wish to be understood as limiting myself in this direction.

In some cases it is desirable, to find the grand total of two or more columns of figures. This may be accomplished upon my machine, in a simple manner, as hereafter described. Upon the end of the shaft 20, is arranged a cog-wheel 68, meshing with a similar cog-wheel 69, arranged to rotate at the same rate of speed, mounted on a shaft 70, (see Figures 2, and 7). Upon the shaft 70 is arranged an additional series of numeral wheels 71, similar in construction and arrangement to those shown upon the shaft 20. Longitudinally movable slides 72, similar in construction and arrangement with the slides 42, together with levers 73, operating a clutch member 74, and carrying

wheels 75, mounted on a parallel shaft 76, all substantially the same in construction and operation with those heretofore described, serve to transmit the rotation of the shaft 70 to the several indicator wheels as 70 has been heretofore described. The several parts are so proportioned arranged and timed, that the rotation of the shaft 20 is transmitted to the shaft 70, as indicated, while an extension 76 1/2, formed on the carriage 43, carries an extending arm 77, similar in construction and arrangement with the arm 44, heretofore described. It will be observed that if but one series of indicator wheels is arranged on the shaft 80 20, but one arm 77, will be necessary, and upon the proper arrangement of the parts the indicator wheels on the shaft 70, will indicate in unison with those upon the shaft 20, in a continuous operation. If however 85 a plurality of series of indicator wheels are used, as indicated in Figure 2, of the drawings, then the extension 76 1/2, must be provided with an extending arm for each series of indicator wheels. A second arm is, therefore, shown at 77 1/2. The said arms are arranged to be in proper position to operate the indicating device on shaft 70, according to the movement of the particular series of wheels on the shaft 20, for which 90 said arm 77, or 77 1/2, may be arranged.

For example in the construction shown in Figure 2, the arm 77, at the right of the extension 76 1/2 will operate the indicating device when the series of indicator wheels 100 at the left on the shaft 20 are operated. When that column of figures has been totaled the series of wheels on the shaft 20, and on the shaft 70, will both indicate the proper totaling. At this point, however, 105 the carriage is shifted to the right for the purpose of operating the series of indicating wheels at the right on the shaft 20. This will bring the extension 77 1/2, shown on the left of the extension 76 1/2, into 110 proper position to operate the indicator wheels on the shaft 70. By this means when the adding of the column of numbers represented by the second series of indicator wheels on the shaft 20 is completed, the 115 grand total of both columns of numbers will be indicated by the indicator wheels positioned upon the shaft 70. Figure 18, shows the machine particularly arranged to total four separate columns, there being four 120 sets or series of indicator wheels upon the shaft 20, each of which will represent a separate column of numbers. The indicator wheels on the shaft 70 will indicate the grand total of all of them while each 125 series on the shaft 20 will indicate the total of its particular column.

The machine is also constructed so that the indicators upon the shaft 70, instead of giving the grand total, will show the differ- 130

ence between the sums of two columns of numbers. As shown the cog-wheel 69, is loosely mounted upon the shaft 70, and carrying one clutch member 79, while the second clutch member 80, is mounted upon and rotates with the shaft 70 but is longitudinally movable thereon. A shaft or bar is loosely mounted in bearings formed in standards 94, so as to permit of a longitudinal movement of the shaft. An arm 95, secured to the shaft 93, and carried thereby engages the clutch member 80, on the shaft 70. (Figures 2 and 19). A spring 81, or equivalent means, tends to force the shaft 93, and the clutch member 80, in a direction to normally engage the clutch 80, 79, when the rotation of the wheel 69, will be transmitted to the shaft 70, with the result before stated. A cog-wheel 83, is loosely mounted upon the shaft 70, the two wheels 82, and 83, being in line (Figures 2 and 4). An intermediate cog-wheel 84, meshing with both the cog-wheels 82 and 83, causes them to rotate in the same direction and in unison. The cog-wheel 83, carries a clutch member 85, while the shaft 70, carries the companion member 86 rotating therewith, and longitudinally movable thereon. An arm 96, is secured to the shaft or bar 93, and controls the clutch member 86, (Figure 19).

As shown in Figures 4, 5, and 19, a sleeve or equivalent means is secured to the shaft 93, or formed thereon and an annular lever 88, pivotally connected as at 89, engages the sleeve 87, in such a manner that the horizontal oscillation of the lever 88, will longitudinally move the shaft 93, and control the operation of the clutches on the shaft 70. An extending bar or arm 90, carried by the carriage 43, is constructed to contact with the lever 88, as the carriage is in proper position by accident or otherwise, inasmuch as the locking means are not particularly applied to those particular wheels. The levers 35, as applied to those particular wheels upon the right of the series, do not engage a locking and carrying wheel, as there is no lower order from which such amount should be carried. This is clearly shown in Figure 2. The end of the levers are provided with a spring 102, engaging with a part to properly return the clutches and levers 35, to their proper and normal position. A pointer 103, shown particularly in Figures 1, and 8, is employed to indicate the proper position of the carriage 43, during the operation of the device. A handle 104, or equivalent means is also provided for reversing the position of the carriage after a number has been indicated as before set forth.

The key indicating the character 0, is not provided with a bar 11, as it will not be necessary for this to transmit motion to the shaft 20, operating that key. It is however,

provided with usual vertical bar 53, and rotates the shaft 52, as before set forth. Thus operating the escapement device and permitting the carriage to move one interval to the right to be in position for the next number indicated.

It is obvious that as to which particular numeral wheel will be engaged with the shaft and operated thereby, when a key is depressed, will depend upon the position of the carriage 43. Hence where in the specification or claims I have referred to means for transmitting the movement of either of the keys to engage "either of the indicator wheels" with the shaft, or where therein I have said to engage "its indicator wheel" with the shaft, I wish to be understood as meaning means for transmitting the movement of the keys to either of the indicator wheels to engage the same with the shaft, depending upon the position of the connecting means.

It is obvious that various modifications may be made without departing from the spirit of my invention, and I do not wish to be understood as limiting myself to the exact form and construction shown.

Having thus described my invention, what I claim as new and desire to secure by Letters Patent is:

1. In a computing machine, operating keys, a shaft, an intermediate mechanism transmitting the movement of either of the keys to the shaft and rotating the same a distance dependent upon the particular key operated, a second shaft driven by the first, indicator wheels loosely mounted thereon, and clutch mechanism for engaging each of the wheels with the shaft, in combination with a transversely movable carriage arranged to operate the clutch mechanism, and controlling mechanism connecting the carriage with the several keys, whereby the movement of a key will rotate the second shaft a fixed distance and engage an indicator wheel with said shaft.

2. In a computing machine, operating keys, a shaft and means for rotating the shaft a distance dependent upon the particular key depressed, in combination with a plurality of indicator wheels, loosely mounted upon the shaft each carrying one member of a clutch device, a second clutch member secured to and longitudinally movable on the shaft, a lever, engaging the second clutch member, a carriage, and means including a part projecting from the carriage to move the lever.

3. In a computing machine, operating keys, a shaft, means for rotating the shaft a distance dependent upon the particular key operated, and a plurality of indicator wheels loosely mounted upon the shaft, and each provided with one member of a clutch device, in combination with a second com-

- plemental clutch member secured to the shaft but longitudinally movable thereon, levers each engaging a second clutch member and by its oscillation adapted to longitudinally move said clutch member on the shaft, longitudinally movable arms each arranged to contact with and operate a lever, a transversely movable carriage arranged in its travel to contact with the arms and move the same, means tending to constantly draw the said carriage in one direction, and for moving said carriage one step upon the operation of any one of the keys, substantially as described.
4. In a device of the kind described, a plurality of movable keys, and a corresponding number of longitudinally movable key operated bars, in combination with a corresponding number of bars, each provided with a stop or shoulder arranged in line with the travel of the adjacent key operated bar, the several stops extending in a diagonal direction across the machine, indicator wheels, and means for transmitting the various movements of said bars to the indicator wheels.
5. In a device of the kind described, keys, a corresponding number of bars, operated by the keys, a corresponding number of shouldered bars arranged in the line of the travel of the key operated bars, whereby each shouldered bar is moved a different distance, a shaft rotated by the shouldered bars, a second shaft driven by the first, and indicator wheels mounted thereon.
6. In a device of the kind described, keys, a shaft, corresponding bars operated by the keys, a corresponding number of shouldered bars to rotate the shaft a distance dependent upon the particular key operated, a second shaft driven by the first, indicator wheels loosely mounted thereon, a clutch mechanism for the indicator wheels, and means controlled by the keys to operate the clutch mechanism of either of the indicator wheels.
7. In a device of the kind described, keys, movable bars, each adapted to be operated by one of the keys, stop bars, the several stops extending in a diagonal direction across the machine, whereby each stop bar is actuated a specific distance varying from all the others, a shaft, a plurality of ratchet wheels mounted upon said shaft, a plurality of arms loosely mounted upon the shaft in proximity to the several ratchet wheels, each arm carrying a pawl adapted to engage a ratchet wheel, and links connecting the stop bars with the arms to oscillate the same, a second shaft driven by the first, indicator wheels loosely mounted thereon, and means for transmitting the movement of either of the keys to either of the indicator wheels and means for temporarily locking said wheels.
8. In a device of the kind described, keys, a corresponding number of longitudinally movable bars, each operated by one of the keys, a corresponding number of longitudinally movable stop bars, each provided with a stop or shoulder arranged in line with the travel of the adjacent key operated bar, the several stops extending in a diagonal direction across the machine, whereby each stop bar is actuated a specific distance varying from the others, a shaft, means for operating the shaft from the stop bars, a second shaft driven by the first, and indicator wheels loosely mounted on the second shaft and clutch mechanism for independently engaging each of the several wheels with the second shaft.
9. In a device of the kind described, a plurality of keys, a corresponding number of key operated bars, a corresponding number of longitudinally movable stop bars, the several stops extending in a diagonal direction across the machine whereby each stop bar, is moved a distance different from the others, a shaft operated by the stop bars, a second shaft driven by the first, indicator wheels loosely mounted on the second shaft, clutch mechanism for connecting the several wheels with the shaft, and a movable carriage arranged to operate the clutch mechanism.
10. In a computing machine, operating keys, a shaft, means for rotating the shaft a distance dependent upon the particular key operated, and a plurality of indicator wheels, loosely mounted upon the shaft in a plurality of series, each of said wheels being provided with one member of a clutch device, in combination with a second complementary clutch member secured to the shaft but longitudinally movable thereon, levers, each engaging one of the clutch members and adapted by its oscillation to longitudinally move said clutch member on the shaft to engage the clutch member of one of the wheels, longitudinally movable arms, each arranged to contact with and operate a lever, a transversely movable carriage arranged in its travel to contact with the arms and move the same, means tending constantly to draw the carriage in its operative direction, and means for releasing said carriage for one interval of movement upon the operation of any one of the keys, substantially as described.
11. In a device of the kind described, a shaft, a plurality of indicator wheels loosely mounted thereon, clutch mechanism for each of said wheels adapted to connect the wheel with the shaft, and means for rotating the clutch mechanism, in combination with a parallel shaft, carrying wheels loosely mounted thereon, each engaging two adjacent indicator wheels, whereby the complete rotation of one indicator wheel will advance

that of the next higher order one interval, and controlling means common to a clutch and carrying wheel.

12. In a device of the kind described, a shaft, a plurality of indicator wheels loosely mounted upon the shaft and arranged in a plurality of series, clutch mechanism for each of said wheels adapted to engage the same with the shaft, and means for rotating the shaft, in combination with a parallel shaft, carrying wheels loosely mounted thereon, each engaging two adjacent indicator wheels, whereby the complete rotation of one indicator wheel will advance that of the next higher order one increment, and levers each controlling a clutch and carrying wheel.

13. In a computing machine, operating keys, a shaft, means for rotating the shaft a distance dependent upon the particular key operated, a plurality of indicator wheels loosely mounted upon the shaft and arranged in a plurality of series, a second shaft driven by the shaft first named, indicator wheels loosely mounted on the second shaft, and means operative upon the movement of either of the keys to connect either of the indicator wheels of either series on the first shaft with said shaft, and to connect a corresponding indicator on the second shaft, whereby the totals indicated on several series of indicators on the first shaft will be indicated as a grand total on the indicators on the second shaft.

14. In a computing machine, operating keys, a first shaft, means for rotating the shaft a distance dependent upon the particular key operated, a plurality of indicator wheels loosely mounted upon said shaft and arranged in a plurality of series, means for advancing an indicator wheel of higher order one increment to indicate a complete cycle of the indicator of a lower order, a second shaft driven by the first shaft, indicator wheels loosely mounted on the second shaft, means for carrying from the lower order to the higher order of said indicator wheels, and key controlled means for connecting either of indicator wheels of either series of the first shaft with said shaft, and to simultaneously connect the corresponding indicator on the second shaft.

15. In a computing machine, operating keys, a first shaft, means for rotating the shaft a distance dependent upon the particular key operated, a plurality of indicator wheels loosely mounted upon the shaft, and arranged in a plurality of series, means for carrying from a lower order to a higher order of said indicator wheels, a second shaft, mechanism for rotating the second shaft in either direction, from the first shaft, indicator wheels loosely mounted on the second shaft, means for carrying from the lower order to a higher order of the indicators, key

controlled means for connecting either of the indicator wheels of either series on the first shaft to said shaft, and for simultaneously connecting the corresponding indicator on the second shaft with said second shaft, whereby there may be indicated on the indicators on the second shaft the sum total or the difference between the totals indicated by two series of indicator wheels on the first shaft.

16. In a computing machine, computing mechanism comprising a first shaft provided with two gear wheels secured thereto, means for rotating the shaft, a plurality of series of indicator wheels mounted on the shaft, and means for engaging each of the indicator wheels with the shaft in combination with a second shaft, provided with gear wheels loosely mounted thereon, one of said gear wheels being in mesh with one gear wheel on the first shaft, and the other with an intermediate gear wheel driven by the second gear wheel on the first shaft, and means for engaging either of the gear wheels on the second shaft with said shaft, whereby the said second shaft may be rotated in either direction, a plurality of indicator wheels loosely mounted on the second shaft, and mechanism whereby the several indicator wheels on the second shaft may be operated by said shaft as the indicator wheels of either series on the first shaft are operated.

17. The combination with a plurality of computing devices each including denominational members and carrying means, of a single operating shaft on which said computing devices are carried, an additional computing device, an additional operating member therefor, a movable carriage, means controlled by the carriage for connecting the first named computing devices with the operating shaft, and means also controlled by the carriage for connecting the additional computing device to the additional operating member to be operated thereby in correspondence with each of the computing devices first named.

18. The combination with a shaft, of a plurality of computing devices each including a series of denominational members mounted on said shaft, carrying mechanism for each of said computing devices, an additional shaft, an additional computing device including a series of denominational members mounted on said additional shaft and having carrying means, a carriage, mechanism controlled by the carriage for connecting the denominational members of the respective computing devices to the respective shafts, and means for operating the shafts.

19. The combination with a shaft, of a plurality of computing devices each including carrying means and a plurality of denominational members mounted on said shaft, of means for rotating the shaft,

means for connecting any desired denominational member with the shaft, an additional shaft, a series of denominational members mounted thereon, carrying means for said members, means for connecting to the additional shaft a denominational member corresponding in denominational position to a denominational member connected to the first named shaft, and variable gearing whereby the operation of the first named shaft will rotate the additional shaft in either direction.

20. The combination with a plurality of computing devices each including denominational members and carrying means, of an additional computing device also including a series of denominational members and carrying means, and means including numeral keys and operating shafts for operating corresponding denominational members of different computing devices simultaneously and in either the same or opposite directions.

21. The combination with a plurality of computing devices, operating shafts therefor, a series of keys for operating the shafts simultaneously, and means under the control of the keys for connecting corresponding denominational members of different computing devices to the shafts.

22. The combination with a shaft, series of denominational members thereon, carrying mechanism for each series of denominational members, a second shaft, a series of denominational members thereon, carrying mechanism for said members, key controlled means for effecting an operative connection of any desired denominational member with the first shaft, key controlled means for operatively connecting a denominational member of corresponding order to the second shaft, and key controlled means for effecting the simultaneous operation of the two shafts to operate the denominational members connected thereto.

23. The combination with a pair of shafts, a series of keys, means whereby the depression of a key will result in the operation of both shafts, series of denominational members associated with one of the shafts and having carrying mechanism, a series of denominational members associated with the other shaft and likewise having carrying mechanism, and means controlled by the keys for effecting an operative connection between denominational members of corresponding order and the respective shafts.

24. The combination with a pair of shafts, a series of keys, means whereby the depression of a key will result in the operation of both shafts in the same or different directions, a series of denominational members associated with one of the shafts and having carrying mechanism, a series of denominational members associated with the other shaft and likewise having carrying mechanism, and means controlled by the keys for effecting an operative connection between denominational members of corresponding order and the respective shafts.

tional members associated with the other shaft and likewise having carrying mechanism, and means controlled by the keys for effecting an operative connection between denominational members of corresponding order and the respective shafts.

25. The combination with a computing device including a series of denominational members and carrying means, of an operating shaft common to the denominational members, clutches controlling the connection of said members with the shaft, a traveling carriage and a plurality of clutch-operating devices movable with the carriage, and means for operating the shaft in either direction.

26. The combination with two computing devices, keys and an additional computing device, of a key controlled driving shaft common to all said devices, a carriage, means operated by the carriage to connect the first named computing devices successively with the shaft and a plurality of devices operated by the carriage to bring the additional computing device repeatedly under the control of the keys.

27. The combination with a plurality of computing devices and operating keys, of a single controlling device common to a plurality of computing devices to control the operation thereof by the keys, a single computing device, an operating shaft and a plurality of controlling devices common to the single computing device to repeatedly connect the same with the shaft.

28. The combination with two computing devices, a common operating shaft therefor, an additional computing device and an additional operating shaft therefor, of keys controlling the operation of all of the computing devices by the shafts, a carriage, means operated by the carriage to bring the first named computing devices successively under the control of the keys through the medium of the first named operating shaft, and a plurality of devices operated by the carriage to bring the additional computing device repeatedly under the control of the keys through the medium of the additional operating shaft.

29. The combination with a plurality of computing devices and keys, of a plurality of operating shafts for the computing devices, a single controlling device common to a plurality of computing devices to control the operation thereof through the medium of the keys and one operating shaft, and a plurality of controlling devices common to a single computing device to repeatedly control the operation thereof by the other operating shaft.

30. The combination with two computing devices, a single operating shaft common to said devices, an additional computing device, an additional operating shaft therefor

and keys controlling the operation of both operating shafts, of a carriage, a device operated by the carriage successively to bring the first named computing devices into successive operation through the medium of the single operating shaft and a plurality of devices operated by the carriage to bring the additional computing device into operation repeatedly through the medium of the additional operating shaft and in unison

with the operations of the two computing devices first named.

In testimony whereof, I have hereunto signed my name in the presence of two subscribing witnesses.

EMANUEL RICHTER.
